UNITED STATES PATENT OFFICE.

JOSEPH PAUPA, OF CHICAGO, ILLINOIS; UNION TRUST COMPANY, EXECUTOR OF SAID JOSEPH PAUPA, DECEASED, ASSIGNOR TO JOSEPH PAUPA AND ANNA K. VOLSCHE, BOTH OF CHICAGO, ILLINOIS.

AUTOMATIC VENDING MACHINE.

Application filed December 4, 1922. Serial No. 604,779.

This invention relates to improvements in automatic vending machines, and particularly to improvements in machines through which upon deposition of a coin of predetermined value a rotary support for the article to be delivered is freed for rotary movement, whereby the purchaser may withdraw from the machine a predetermined length of the article. While the machine is described in the following with reference to the sale of a predetermined length of a web of paper, as for instance paper towels, it will naturally find application to many other uses.

15 It is an object of the invention to support a spool or bobbin of the material in such manner that the material may be dispensed by rotation of the support, and to effect a manual control, the control means being normally locked and being released upon deposition of a coin of predetermined value only.

It is another object of the invention to arrange a lock for a rotary member and to utilize a coin as a connecting element between a handle member and a device which holds the member against rotation, whereby upon actuating the handle, the device will be actuated by the coin to be subsequently returned automatically to locking position, the coin also being released from engagement with the locking device.

The invention also has the object of arresting the coin in such relation with respect to the locking member that a very short movement of the control member will suffice to produce a relatively long movement at one end of the locking member to safely carry said end to release position.

40 The invention also has the object of effecting the opening of a gate through which the strip or article to be dispensed may be withdrawn, the opening movement of the gate being controlled from a rotary element which normally is locked against movement.

45 It is also an object of the invention to combine with the gate control mechanism in addition to the means for positively moving the gate to opening position, means for drawing the gate normally toward closing position and additional means for forcing the gate into absolute tight closing position.

With these and other objects in view, an embodiment of the invention is described in

the following specification and is illustrated in the accompanying drawings.

55

Fig. 1 is a front view of the device, the cover plate being removed;

Fig. 2 is a vertical sectional view of the same on line 2—2 of Fig. 1, parts being shown broken away to reveal a portion of the 60 coin control and gearing;

Fig. 3 is a front elevation of the coin controlled locking mechanism in locking position;

Fig. 4 is a similar view showing the mechanism in release position;

Fig. 5 is a detail view of the mechanism for drawing the gate to closing position.

The container 1, preferably in the shape of a rectangular casing, is provided with 70 grooves 2 on opposite side walls to permit of the insertion of a roller or spindle 3 on which the spool of paper or other flexible material 4 to be dispensed, is stored. A catch, generally indicated at 5, permits the 75 introduction of the journals of this spool through the grooves 2 to the ends of the groove which are deflected downward; a removal of this spool can only be had upon withdrawal or elevation of the catch 5, and 80 this again may be effected only upon removal of the cover of the casing which is not shown. The lateral walls of the container furthermore pivotally support by means of brackets 6 secured near the front edge of the 85 side walls, a gate 7. The lower edge of the gate projects into a recess 9 near the front edge of the bottom 10 of the container, while the pivots 11 are near the upper end of the gate. The latter is connected near its lower 90 edge by means of links 12 with the ends of springs 13, the other ends of which are anchored at 14 on the side walls of the casing. These springs 13 acting on the rear ends of the links 12 therefore have a tendency to force the gate into open position. The links 12 are movably connected by pin and slot arrangement 15 with the lower ends 95 of bars 16 which are pivotally supported at the top at 17 on the side walls of the casing. Other springs 18, heavier and stiffer than springs 13 and connected with the links in front of the bars 16 and anchored also at the lower ends of the depending bars, serve for effecting a complete closure of the gate 7 100 when the bars are held in retracted position.

105

The release of the gate to open position to permit the withdrawal of the web W is under control of a device L which may be operated upon insertion of a coin. This device 5 also controls a gearing generally indicated at 20 and associated with a conveying roller 21 by means of which the web W may be withdrawn from the part 3 on which it is stored. This feeding operation is advisably 10 enhanced by the provision of a roughened surface on the roller 21 and by the arrangement of a companion roller 22 which engages the fabric or web W of paper on the side opposite to that on which the roller 21 engages 15 the same. This second roller 22 also is provided with a roughened surface and as the two rollers are in frictional engagement with opposite surfaces of the web, a positive feeding action will be obtained upon rotation of either one of said rollers, and particularly upon rotation of roller 21.

The roller 21 carries at one end a gear 23 which is in engagement with a relatively large gear 24 under direct control of the coin 25 device L. Both of the gear elements 23 and 24 are mounted in a recess or pocket 25 in one of the side walls of the container and may be adjacent a casing 26 which is fastened to the outer surface of the container 30 and which incloses the coin control mechanism L. Upon rotation of the larger gear 24 rotation at increased speed will be transmitted to the pinion 23, which will thereby effect rotation of the conveying roller 21 for carrying frictionally a predetermined length 35 of the web W through the gate.

The coin controlled locking mechanism is arranged to effect a predetermined number of revolutions of the larger gear 24 and to 40 lock said gear again after having gone through this movement. Hence the conveying roller 21 also can make only a predetermined number of revolutions and, depending upon the circumference of this roller, the 45 length of material W which can be dispensed from the container upon deposition of a coin is exactly predetermined.

The coin control mechanism L in the embodiment illustrated comprises the casing 26 which is secured to the outer surface of one 50 side wall of the container, preferably in such manner that the attachment means are not accessible to tampering. The outer wall 28 of the casing 26 is provided with a slot 27 through which a coin of a predetermined size 55 may be inserted. The inner surface of the wall 28 is equipped adjacent the coin slot 27 with a chute 29 through which the coin C inserted into the slot is moved by gravity 60 in an inclined direction, sliding off the chute and onto the rear portion of a lever 30 which is pivoted at 31 below said rear portion on a stud 32 projecting from the wall 28 of the casing. The rear portion of the lever 65 comprises two inclined walls 33, 34, which are

parallel to each other and which, in the normal position of the lever 30 are arranged in such angular position that the coin upon sliding off the chute 29 enters the space between these walls 33, 34. This receiving 70 pocket for the coin is confined opposite the wall 28 by the rear wall 36 of the casing, to prevent lateral discharge of the coin and to prevent also that a coin of a size larger than desired should enter between the two walls 75 of the pocket.

The front end of the lever 30 is provided with a locking detent 37 which extends downward and which normally is in locking engagement with a detent or projection 80 38 of a rotary element 39 secured to a shaft 40. The latter is supported in the wall 28 of the casing 26 and also extends transversely through the container 1. Rotation of the shaft 40 therefore may only be effected 85 upon withdrawal of the locking finger 37 from the element 39 and this withdrawal takes place upon insertion of a coin and the subsequent attempt of rotating the shaft 40.

That part of the coin C which has slid 90 from the chute 29 into and partly through the pocket formed by walls 33, 34, comes to rest on a projection 42 of the element 39, this projection being normally located in line with the lower edge of the pocket in the 95 lever 30. As long as no coin is inserted the element 39 and hence also shaft 40 are locked against rotation by the finger 37 of the lever 30 and if this finger would be raised the element 39 could pass below the lever 30. The 100 projection 42 at the rear end of the segment, however, and normally located in the path of the coin, supports the coin in a position in which this coin is still partly inserted in the pocket of the lever 30, the coin thereby 105 becoming the operative connecting link between the element 39 and the lever.

If now an attempt is made to rotate the element 39 the coin partly resting on the projection 42 of the element and partly 110 resting in the pocket of the lever 30, will act to transmit this part rotation to the lever and thereby to raise the holding finger 37 out of the path of the front projection 38 of the element 39. The element 39 and shaft 115 40 can then be rotated and after having gone through a small arc the rear projection 42 will pass beneath the coin which is retained in the pocket, the pocket having been turned by the coin to approximately 120 horizontal position. As soon as the projection 42 has gone beyond the edge of the coin C a spring 43 secured near the rear end of the lever 30 at one end and having its other end anchored on the wall of the casing, will 125 draw the lever 30 down again into the position in which it was before the coin was inserted. As the rotary element 39 however has gone past the lower end of the coin pocket the coin will now drop from the 130

5 pocket into a coin box or some other suitable receptacle (not shown) or into the lower part of the casing. The projection 42 is located in a vertical plane different from that of the detent 37, so as to pass by said 10 detent, even though the same be returned to locking position (Fig. 3). The movement of the rotary element 39 with the shaft 40 secured thereto can now be continued until 15 the front end 38 of the element 39 again approaches the holding detent or finger 37 of the lever 30, in which position the parts are again locked against continuation of the rotation in the same direction. Rotation 20 in the opposite direction is prevented at all times owing to the arrangement of a ratchet wheel 44 fixedly connected with the shaft 40 and a pawl 45 forced by a spring 46 into engagement with the surface of the 25 teeth of the ratchet so as to permit of rotation of said ratchet in one direction only.

For the purpose of facilitating the rotation of the shaft 40 on which the locking element 39 is mounted, the shaft carries a 25 knob or handle 47, which projects from the casing 26. The shaft 40 has a bearing in the wall 28 of the coin control mechanism and its other end is suitably supported in a bearing in the opposite side wall of the container. 30

As the gear 24 on shaft 40 meshes with the pinion 23 on the conveyer roller 21 for frictionally engaging the web material and as the shaft 40 is stopped after completion 35 of one revolution, the conveyer roller also will only make a predetermined number of revolutions so that with the deposition of a coin a predetermined length of strip will be removed from the spool and carried to the 40 gate.

The shaft 40 on which the gear 24 is mounted also is instrumental for ordinarily maintaining the gate in closing position. For this purpose one or more cams or eccentrics 50 are secured to the shaft (one cam only being shown); these eccentrics frictionally engage in normal position, i. e., when the shaft is at rest, a transverse bar 51 which connects the bars 16 that are associated with 45 the gate 7. The transverse rod 51 also serves to stiffen the gate actuating structure, and a collar or enlargement 52 secured in some suitable way to rod 57 absorbs the wear caused by the frictional engagement of the eccentrics, arms or cams 50 mounted on the shaft 40. The length of these arms is selected so as to force the bars 16 rearwardly about their pivot points 17 and against the rear end of the slot in the links 12, thereby 50 forcing back these links and tensioning the springs interposed between the links and the fixed point 14 of the container. Upon rotating the shaft 40, after deposition of the coin, the eccentrics or arms 50 secured to the shaft 40 will pass beyond the enlarge- 65

ment 52 of the rod 51 and as soon as they have slipped off the enlargement, the springs 13 will cause the links 12 to advance and to move thereby the gate 7 to open position. The springs 18 are not tensioned in this 70 movement. The springs 13 will then maintain the gate open until the eccentrics or arms 50 mounted on the shaft 40, after nearly completing the entire revolution of the shaft, again frictionally act on the enlargement 52 attached to the transverse rod 51 and their eccentric operative surfaces will force the rod and the bars 16 against the tension of the springs 13 back, thereby also forcing the gate towards closing position. 75 In the meantime, however, a predetermined length of web material W has been conveyed through the opened gate outward. 80

As the springs 13 act on the links 12 only for forcing the gate outward to open position, and as the eccentrics or cams 50 act on the bars 16 only for forcing the gate towards closing position, a tight actual closure of the gate could only be obtained if the eccentrics or cams 50 would be suitably 90 finished with an exactness which ordinarily is not required and which for manufacturing reasons not desirable in a device of this character. In order to actually bring the gate into closing position (even though the engagement of the cams 50 with the enlargement 52 of the rod 51 would not induce the gate to engage the edge of the container), the springs 18 are secured between the links 12 and the bars 16. After the bars 16 are forced rearwardly by the cams 50 into engagement with the ends of the slots in the links 12, the springs 18 are practically anchored at their rear ends to the bars 16 and exert a pulling effect on the 100 links 12, so that the gate 7 will be pressed against the edge of the container, to tightly 105 close the discharge slot 9.

The companion roller 22 which coacts with the conveyance roller 2 for carrying a strip of web material W to the slot 9 is preferably supported in spring controlled bearings 60, each inserted into a recess 61 in the side walls of the container C. In this way the companion roller 22 will always be forced frictionally into contact with the conveyer roller 21 or into contact with that strip of paper respectively which has been inserted between the conveyer and the companion roller, forcing the paper into engagement with the conveyer roller and assuring thereby that upon each rotation of the conveyer roller a predetermined length of strip is carried from the spool. 110 115 120

The operation of the device is as follows: 125 The container is charged by removing the front cover (not shown in the drawing) and inserting that member on which the web material to be dispensed in the apparatus 130 is stored; in the present case this member

is represented by a spool of paper. The spindle 3 or bobbin of the spool is rotatably supported in suitable pockets of the side walls and is held against withdrawal by the catch. The free end of the web material W is threaded from the spool through the space between the rollers 21 and 22, the smaller companion roller 22 being supported in spring controlled bearings 60 which permit the withdrawal of the roller 22 from engagement with the roller 21 to facilitate the threading of the web through the space between the two rollers; and the free end of the web is then pushed out through the slot 10, which is normally covered by the yielding gate.

The cover of the container is then restored in place and locked in a suitable way so as to protect the contents against tampering.

Rotation of the shaft 40 in counter-clockwise direction cannot be effected by the knob or handle 47 as the sector 39 is stopped by the depending end 37 of the lever 30, while rotation in the other direction is rendered impossible through the arrangement of the ratchet device.

Upon insertion of a coin into the slot 27 the coin will drop through the chute so as to lie partly on the rear end 42 of the sector 39 and partly on the lever 30 between the walls 33 and 34. If now the knob 47 is turned counter-clockwise, the upward movement of the rear end 42 of the sector 39 is through the coin C transmitted to the lever 30, the coin being acted on from one side by the part 42 and acting with the other side against lever 30. This will remove the finger 37 from the front end 38 of the sector 39 so as to release the shaft 40 for rotation. In the continued rotation of the shaft 40 two operations take place.

The gearing controlled by the shaft 40 imparts rotation to the conveyer roller 21 so as to unwind a part of the web material and feed said web material in direction towards the slot 9. At the same time, right at the beginning of the rotation of the shaft 40, the cam 50 is moved out of engagement with the enlargement 52 on the shaft 51, thereby releasing the gate controlling structure which consists of the bars 16 and links 12, to the action of the spring 13. The springs immediately force the links 12 and thereby the gate 7 forwardly, to move the gate to open position. That part of the web material which is forcibly taken off the stored quantity is thereby fed through the slot as long as the rotation of the roller 21 continues.

Short time after the rotation of the shaft 40 in counter-clockwise direction has set in, the rear part 42 of the sector 39 passes below the end of the coin and the latter drops into the lower part of the casing 26 in which a coin box (not shown) may be disposed.

When this has taken place, the spring 43 draws the lever 30 downwardly until the detent 37 of the lever rests on a boss 49 which projects from the inner surface of the casing 26 inwardly. In this position the detent 37 again will enter into locking engagement with the forward projection 38 of the sector 39 when the latter after completion of one revolution strikes against said detent.

Towards the end of the revolution the cam 50 again is forced towards the transverse rod 51 connecting the bars 16, so as to move these bars, and thereby also the links 12, towards the rear of the container C. This will also move the gate towards closing position and the movement into tight closing position is completed by springs 18 which are interposed between the lower ends of the bars 16 and the links 12 to force these links against the action of the springs 13 rearwardly until the gate at its lower edge is in touch with the rear edge of the slot 9. The gate therefore is opened at the beginning and closed at the end of the operative movement. The paper discharged from the slot may now be withdrawn by being torn off along the edge of the gate.

A cover 70 is provided in the wall 28 near the lower end thereof. This cover overlies an opening 71 and has at one end on the inner surface thereof, a projecting finger 72 which is spaced from the inner surface of the cover a distance equal to the thickness of the wall of the casing 26, so that the cover may be put in place by inserting it sideways into the opening and then swinging it to closing position towards the wall 28. The other end of the cover 70 is provided with a notched projection 72 adapted to receive the lower end of a vertical bar 73 which is continuously forced downwardly by a spring 74 anchored at its lower end at 75 on the wall of the casing and connected at 76 with a lug on the bar. The projection 72 slants downward and inward so as to readily lift the foot end of the vertical bar 73 when the cover 70 is swung in place. A handle 77 projects from the vertical bar inward into the casing near the front cover of the same. The operator may readily lift this handle to move the bar 73 from locking engagement with the notch whereupon the entire cover 70 can be swung outwardly and can be withdrawn so as to grant access from the outside to the coins deposited in the lower part of the casing 26. When the cover 70 is restored in place, the vertical bar 73 will automatically be forced into locking engagement with the holding notch of the cover.

I claim:

1. In a device of the character described, the combination of an actuating mechanism, a container, means controlled by said mechanism for discharging material stored in said container, a gate, and means for normally

urging said gate to open position, a locking element for rendering said opening means inoperative and another means under control of the actuating mechanism for successively releasing the locking means of the gate to render the opening means operative and for reapplying the locking means.

2. In a device of the character described, the combination of an actuating mechanism, 10 a container, means controlled by said actuating mechanism for imparting discharge movement to merchandise stored in the interior of the container, a gate, means for moving said gate to open position, said means 15 being normally held inoperative and a mechanism controlled by the said actuating mechanism for releasing the gate to the action of said opening means.

3. In a device of the character described, 20 the combination of an actuating mechanism, a container, means under control of the actuating mechanism for discharging material from the container, a gate, springs associated with the gate and having a tendency 25 to normally move said gate to open position, means under control of the actuating mechanism for moving the gate towards closing position, and another set of springs for moving said gate fully into closing position after 30 said second named means have been actuated.

4. In a device of the character described, 35 the combination of an actuating mechanism, a container, means under control of said mechanism for discharging material from

said container, a gate, automatic means for opening said gate, and means operative upon the beginning of the movement of said actuating mechanism for releasing said gate to the action of said automatic means.

5. In a device of the character described, the combination of an actuating mechanism, a container, a gate pivotally mounted on said container, a pair of bars pivoted to said container, links connecting said bars with the gate, and a transverse rod connecting said bars, said mechanism being adapted to engage said transverse rod to impart movement to the gate.

6. In a device of the character described, the combination of an actuating mechanism, a container, a gate movably mounted on the container, bars pivoted to the container, a transverse rod connecting the bars, links interposed between said bars and the gate, said mechanism including means for intermittently actuating said transverse rod to effect movement of the gate.

7. In a device of the character described, the combination of an actuating mechanism, a container, a gate for said container, a pair of bars pivoted to said container and connected with said gate, a transverse rod connecting said bars, an enlargement on said transverse rod, and means under control of the actuating mechanism for intermittently acting on said enlargement to close the gate.

In witness whereof I affix my signature.

JOSEPH PAUPA.
